UNITED STATES PATENT OFFICE

HEINRICH HACKL, OF HEUFELD, GERMANY

MANUFACTURE OF BISULPHITE LIQUOR AND DIMAGNESIUM PHOSPHATE

Application filed March 21, 1929, Serial No. 348,999, and in Germany March 27, 1928.

The cellulose industry consumes large quantities of bisulphite liquor which is generally obtained by dissolving limestone in sulphurous acid. This calcium bisulphite liquor is, however, not the best but only the cheapest sulphite liquor for the boilings. Compounds of magnesium and of sodium with sulphurous acid afford many advantages but their preparation according to the present state of the art, is too expensive. I have invented a new process by which compounds of magnesium and of sodium with sulphurous acid may be more cheaply prepared.

It is known that solutions of crude phosphate in sulphurous acid with simultaneous or subsequent addition of magnesium sulphate and removal of the gypsum which is formed, can be used as crude liquors of monomagnesium phosphate and magnesium bisulphite with an excess of free sulphurous acid. According to this process dimagnesium phosphate can be separated from these liquors by the addition of magnesium compounds having a basic character. The yield of these valuable phosphate fertilizers is, however, very small in comparison with the bisulphite yield, which latter is composed in this process of three quantities.

30 1. Before precipitation takes place, the whole of the free sulphurous acid contained in the liquor must be neutralized by a basic magnesium compound whereby bisulphite is formed.

35 2. For every one molecule of phosphoric acid in the precipitation two molecules of bisulphite remain in the liquor.

3. The calcium carbonate content in the phosphate also passes through the form of calcium bisulphite into the form of magnesium bisulphite in the final liquor. Neglecting the calcium carbonate contained in the crude phosphate but taking into consideration the necessary excess of free sulphurous

acid, the reaction takes place therefore in the following way:

This process requires the introduction of a basic magnesium compound which can only be obtained by artificial means. 55

In contradistinction hereto it has now been found that dimagnesium phosphate and magnesium bisulphite liquor can be obtained in a simpler and cheaper way if the above mentioned crude liquor of monomagnesium phosphate and magnesium bisulphite be heated under normal or reduced pressure. Firstly, the whole of the free sulphurous acid escapes, as such, after which, on further raising the temperature, dimagnesium phosphate is precipitated with the evolution of sulphurous acid from the corresponding quantity of bisulphite and there remains, to the end of the boiling, a precipitate which consists substantially of dimagnesium phosphate and a liquor of magnesium bisulphite but in much more favourable relative proportion than in the process known hitherto. The reaction takes place in the following way:— 65

In accordance with this invention, therefore, less than half the quantity of bisulphite is obtained with the same quantity of dimagnesium phosphate as compared with the known process. Therefore, by the new process more than double the quantity of valuable phosphate fertilizer is made for an equal quantity of bisulphite made by the old processes. The provision of a basic magnesium compound for precipitation is not required and a great portion of the sulphurous acid can be used in a concentrated form for the solution of fresh phosphate. 90

It was not to be expected that magnesium bisulphite would be stable when heated in the presence of dimagnesium phosphate, because the diphosphate has the property when 5 boiled with water, of splitting up into tri-phosphate and monophosphate; neither was it to be expected that, by suitably selecting the conditions of solution, a bisulphite liquor would be obtained which would correspond 10 approximately, as regards its sulphite content to the lime liquors commonly employed in the cellulose industry.

The present process permits of phosphates which, on account of the large amount of 15 calcium carbonate they contain, are only of small value, being treated to form a fertilizer of high percentage, as the calcium carbonate content does not function as a diluent in the solid final product but figures as magnesium 20 bisulphite in the final liquor.

It has also been found that a portion of the magnesium sulphate may be replaced by sodium sulphate, and a sodium bisulphite liquor obtained in addition to dimagnesium 25 phosphate or one mixed with magnesium bisulphite.

The bisulphite liquors are free from lime.

Example.—1650 parts kieserite are dissolved in 16,500 parts water and 1500 parts 30 phosphate Kalaa-es-Djerda, containing approximately 12½% CaCO_3 and approximately 57% $\text{Ca}_3\text{P}_2\text{O}_8$ together with the minor proportions of other ingredients, are added to the solution. The entire mass is treated with 35 gaseous SO_2 (sulfur-dioxide), while being kept agitated, whereby a liquor of about 16° Bé. is obtained which is separated from the gypsum produced and then boiled. The boiling causes about 75% of the amount of SO_2 , 40 contained in the solution to be evolved which, after being cooled down, are again utilized for the dissolving of a fresh mixture of kieserite, phosphate and water, while the remaining about 25% SO_2 retained in the liquor, 45 are replaced by fresh SO_2 -gases.

After boiling for about 1 to 1½ hours the phosphoric acid has been almost completely precipitated as dimagnesium-phosphate. This precipitate, after having been separated 50 from the liquor and after having been dried contains about 33% P_2O_5 which are entirely soluble in citric acid, while the liquor constitutes a solution of magnesium-bisulphite of sufficient strength to be available 55 for boiling the pulp either directly or after having been charged with free SO_2 .

The accompanying flow sheet illustrates diagrammatically the process described.

I claim:—

60 1. The method of producing lime free bisulphite liquors comprising the steps of adding magnesium sulphate to a solution of crude phosphate in sulphurous acid, separating the resulting liquid and solid matters, precipitating dimagnesium phosphate from 65

the said liquid by boiling the same and separating such dimagnesium phosphate from the final bisulphite liquor.

2. The method of producing lime free bisulphite liquors comprising the steps of 70 adding sulphurous acid and magnesium sulphate to crude phosphate, separating the resulting liquid and solid matters, heating the liquid to a temperature such that dimagnesium phosphate is precipitated and withdrawing the final bisulphite liquor from the dimagnesium phosphate. 75

3. The method of producing lime free bisulphite liquors, comprising the steps of 80 adding magnesium sulphate and sodium sulphate to a solution of crude phosphate in sulphurous acid, separating the resulting liquid and solid matters, precipitating dimagnesium phosphate from the said liquid by boiling the same and separating such dimagnesium phosphate from the bisulphite liquor. 85

4. The method of producing lime free bisulphite liquors, comprising the steps of 90 adding sulphurous acid, magnesium sulphate and sodium sulphate to crude phosphate, separating the resulting liquid and solid matters, heating the liquid to a temperature such that dimagnesium phosphate is precipitated and withdrawing the final bisulphite liquor from the dimagnesium phosphate. 95

5. The method of producing lime free bisulphite liquors, comprising the steps of adding magnesium sulphate to a solution of crude phosphate in sulphurous acid, separating the resulting liquid and solid matters, precipitating dimagnesium phosphate from the said liquid by boiling the same under reduced pressure and separating such dimagnesium phosphate from the final bisulphite liquor. 100

6. The method of producing lime free bisulphite liquors, comprising the steps of adding sulphurous acid and magnesium sulphate to crude phosphate, separating the resulting liquid and solid matters, heating the liquid under reduced pressure to a temperature such that dimagnesium phosphate is precipitated and withdrawing the final bisulphite liquor from the dimagnesium phosphate. 110

7. The method of producing lime free bisulphite liquors, comprising the steps of adding magnesium sulphate and sodium sulphate to a solution of crude phosphate in sulphurous acid, separating the resulting liquid and solid matters, precipitating dimagnesium phosphate from the said liquid by boiling the same under reduced pressure and separating such dimagnesium phosphate from the final bisulphite liquor. 120

8. The method of producing lime free bisulphite liquors, comprising the steps of adding sulphurous acid, magnesium sulfate and sodium sulphate to crude phosphate, sep- 125

arating the resulting liquid and solid matters, heating the liquid under reduced pressure to a temperature such that dimagnesium phosphate is precipitated and withdrawing the final bisulphite liquor from the dimagnesium phosphate.

5 9. In the preparation of bisulphite liquors with simultaneous production of dimagnesium phosphate the method of increasing the 10 yield dimagnesium phosphate consisting in subjecting a crude liquor containing monomagnesium phosphate and magnesium bisulphite to a temperature sufficient at the prevailing pressure to cause the dimagnesium 15 phosphate to precipitate from the liquor.

10 10. In the preparation of bisulphite liquors with simultaneous production of dimagnesium phosphate, the method of increasing the 15 yield of dimagnesium phosphate consisting in subjecting a crude liquor containing monomagnesium phosphate, magnesium bisulphite and sodium bisulphite to a temperature sufficient at the prevailing pressure to cause dimagnesium phosphate to precipitate from the liquor.

15 In testimony whereof I have signed by name to this specification.

HEINRICH HACKL.
